REPRODUCER FOR PHONOGRAHS

Leland D. Norton, Bridgeport, Conn., assignor to
Dictaphone Corporation, New York, N. Y., a
corporation of New York

Application April 15, 1935, Serial No. 16,437
Renewed January 18, 1936

10 Claims. (Cl. 274—27)

This invention relates to acoustic reproducers for phonographs and more particularly to improved means for modifying the sound transmitted thereby. An object of the invention is to 5 provide an efficient reproducer and modifier device of simple and compact form and construction. A further object is to provide a sound modifier effectively operable gradually to vary tone and intensity of sound transmitted thereby. Other 10 objects will be in part obvious and in part pointed out hereinafter.

The invention accordingly consists in the features of construction, combinations of elements and arrangements of parts as will be exemplified 15 in the structure to be hereinafter described and the scope of the application of which will be indicated in the following claims.

In the accompanying drawings, in which is shown one of the various possible embodiments of 20 my invention:

Fig. 1 is a sectional view through a portion of a transcribing machine carriage showing the sound-box and sound-modifier mounted thereon. This section is taken on line 1—1 of Fig. 5.

Fig. 2 is a cross-section of the modifier taken 25 on line 2—2 of Fig. 1;

Fig. 3 is a horizontal cross-section of the modifier taken on line 3—3 of Fig. 2;

Fig. 4 is a horizontal cross-section of the modifier taken on line 4—4 of Fig. 2;

Fig. 5 is a top plan view of the modifier;

Figs. 6, 7, 8 and 9 are diagrammatic views showing the relation of the vent port in relation to the valve at successive stages as the modifier occupies "Loud", "Medium", "Soft" and "Off" positions.

Similar reference characters refer to similar parts throughout the several views of the drawings.

As is well known, in the operation of transcribing phonographs the vibrations of a diaphragm, caused by a stylus following the sound track of a sound-record, effect in the sound-box of the machine a succession of sound waves having substantially the same characteristics as those which were recorded upon the phonograph record. These sounds are transmitted from the sound-box through a sound passage associated with the sound-box and ultimately reach the operator's ears through hearing devices of suitable construction. The amplitudes of sound waves thus produced by the diaphragm vary greatly with different records and consequently the volume of sound reaching the ears of the operator also 50 is greatly variable. It is, therefore, advanta-

geous to provide a modifier for the purpose of controlling the sound intensities produced by different records so that the sound received by the operator may be held at a uniform or desirable loudness, by merely adjusting the modifier. 5

It has been found that when the sound passage through a modifier is merely restricted to reduced volume, the sound becomes hollow or muffled because of the disproportionate loss of the sound waves having the higher frequencies. This 10 effect is not produced when the sound is modified by simultaneously allowing a sufficient portion of the energy of the sound waves to escape to the atmosphere. However, a nice balance must at 15 all times be maintained between the degree of restriction of the sound passage and the quantity of sound energy permitted to escape. Heretofore modifiers have been constructed having the characteristic of accomplishing simultaneously a gradual closing of the sound air passage 20 and a gradual opening of the vent passage to the atmosphere. The results attained with such modifiers have not been uniformly satisfactory, due no doubt in many instances to the inclusion of large resonant pockets in the sound passages. 25 Where such pockets exist, and in fact where they do not exist but the air passages themselves are of large volume, it has been found that the resonant effect produced by succeeding sound waves increases rapidly as the sound passage is restricted ahead of the advancing waves. It was 30 therefore thought necessary to increase the vent opening at the same time that the sound passage was diminished.

Experiment has recently revealed the fact that 35 where the sound passages are properly designed by making them as straight as possible and freeing them from resonant pockets, best results are attained by gradually decreasing the amount of venting simultaneously with a gradual restriction of the sound passage. And this result, although 40 contrary to pre-existing opinion, is not surprising when notice is taken of the fact that restriction of the sound passage tends to build up sound wave energy in the sound passage back of the restricted portion thereof. As a consequence the 45 rate at which the sound energy escapes to the atmosphere through the vent opening increases as the sound passage restriction increases. Whether this is the true explanation or not, experiment clearly demonstrates that a reduction in the amount of venting concurrent with restriction of the sound passage results in effective volume control without appreciable loss of clarity or tone quality. 50 55

Now referring to the drawings, the carriage 10 of a transcribing phonograph is provided with an opening 11 in which fits the reproducer and modifier unit, indicated generally by 12. This unit 5 comprises a shallow annular sound-box 13 and a modifier housing 14, the latter seated in a recess 15 formed in the upper part of the former and held in position relatively to the sound-box by means of a set screw 16. The sound-box of the 10 reproducer is provided with a vibratory diaphragm 17 to which is connected a link 18 to actuate a stylus-carrier (not shown) the stylus of which is adapted to track the sound groove of a phonograph record. The vibrations of the diaphragm 15 produced by the phonograph record set up in the air chamber 19 of the sound-box a succession of sound-waves of substantially the same character as those which were recorded.

In the present embodiment the modifier comprises the above mentioned housing 14 and a cylindrical valve member 20 rotatably seated in snug relation to the walls of a cylindrical chamber 21, which chamber extends through the housing 14 and is open at both upper and lower ends. This chamber is connected to the air chamber 19 within the sound-box by means of an inlet passage 22, of restricted diameter relatively to the diameter of the air space 19. The valve chamber 21 is slightly larger in diameter than the passage 22, and the valve cylinder 20 is provided with a passage 23 of substantially the same diameter as the inlet passage 22 coaxially aligned with the said passage 22 and forming a direct continuation thereof. The passage 23 extends upwardly in the valve member a sufficient distance to intersect with an upwardly inclined passage 24, adapted to be brought into alignment with an upwardly inclined outlet passage 25, provided by a tubular member 26 extending through the peripheral wall 40 of the housing 14.

It will be noted that the relation of the outlet passage 25 to the cylindrical valve chamber 21 and also the relation of the valve passage 24 to the valve passage 23 is such that their axes intersect in an angular relation greater than 90°. This arrangement is advantageous in that it eliminates sharp bends in the sound passage. Since, at the junction of the sound passages within the valve member the adjoining walls are curved at 50 as great a radius as is practicable, there is attained, as a result, a passageway from the inlet passage 22 to and through the passageway 25 which is free from sharp bends or other obstructions tending to cause reverberation or produce 55 resonant effects as the sound waves are carried from the diaphragm to the ears of the operator. The tubular member 26 may be connected in the usual manner with hearing devices by means of rubber tubing.

60 At its upper end the valve member is provided with a flat cap portion 27, which, covering the upper end of the housing 14, extends beyond the peripheral walls thereof and provides efficient means for rotating the modifier valve. Occupying positions 90° apart upon the upper surface of the cap appear the index markings "Loud", "Med.", "Soft" and "Off" (see Fig. 5) to indicate the appropriate positions of the valve for loud, medium or soft transmission, and for the completely closed position. These index marks are adapted to be brought respectively into line with a pointer member 28 mounted upon the housing 14.

By reference to Figs. 1, 3 and 4 it will be seen
75 that the housing 14 has formed therein, extend-

ing down from the upper surface thereof, a deep recess 29 seated in the bottom of which is a helical spring 30 adapted at all times to press upwardly against the bottom of a plunger 31 fitting 5 slidingly within the recess 29. When the valve cylinder is assembled in operative relation to the housing 14 this spring presses against the under-side of the valve cap portion 27. The valve is held against axial movement within the housing 14 by means of a screw 32 the inner end of which fits closely between the side walls of an annular groove 33 formed in the valve cylinder 20. The plunger 31 resiliently holds the valve groove in such relation to the screw 32 that the valve and housing passages 24 and 25 respectively may be 10 brought into full registry one with the other when the valve member is turned so that the "Loud" indication upon the cap is opposite the pointer 28. A stop pin 34 seated in the groove 33 engages 15 alternatively the inner end of the screw 32, on opposite sides, to determine the limit positions of the valve, those positions being the "Loud" and "Off" positions. The spring 30 holds the plunger 31 against the cap 27 with sufficient pressure so 20 that the valve is frictionally held in any adjusted 25 position.

Seated in the plane of the horizontal axis of the orifice of valve passage 24 there is shown a V-shaped groove 35 cut in the peripheral wall of the valve cylinder 20, which, starting with a predetermined depth where it intersects the passage 24, extends away from the passage in a clockwise direction as seen in Figs. 1 and 3, and gradually grows shallower until it runs out at a predetermined point indicated in Fig. 3 by the reference numeral 36.

Referring to Fig. 1, a vent opening 37 extends horizontally through the lower portion of the housing 14 and the surrounding wall of the sound-box, connecting the valve chamber 21 with the outer atmosphere. It will be noted that the location of this vent passage is closely adjacent the inlet passage 22 from the sound-box. Since it is desirable to cause a gradual cutting off of communication from the interior of the valve to the atmosphere, through this vent port, at the same time that the sound passage is being restricted by bringing the V-groove 35 into direct communication with the outlet passage 25, the lower end of the valve cylinder is truncated or cut away helically, as illustrated at 38, to provide an advancing helical wall surface capable of being turned across the inner end of the port 37 to control the venting of air through that port.

Reference to Fig. 6 will show the position of the helically cut end of the valve member relatively to the vent port 37 when the valve member stands in the position disclosed in Figs. 1, 2 and 3, namely, in the position for loud transmission with the passage through the valve in full registry with the passage 25. In this position of the ports the vent opening is in full communication with the interior of the valve member and with the inlet passage 22. As shown in Fig. 7, the valve has been turned in a counter-clockwise direction from "Loud" to "Med.". In this position of the parts the sound passage will be partially restricted, the sound passage 24 having passed out of registry with the passage 25 so that the deeper portion of the V-groove 35 serves to conduct the sound waves from the interior of the valve to the interior of the passage 25. Concomitantly with this restriction of the sound passage, the vent passage will have been partially closed. A further quarter-revolution brings the 55 60 65 70 75

valve to the "Soft" position, indicated in Fig. 5, when communication between the inlet valve passage and the valve housing passage will be only by means of the shallow end portion of the 5 V-groove 35. At this time only limited venting will be permitted as indicated by the position of the end wall of the valve member relatively to the vent port in Fig. 8. A further quarter-turn will completely close communication both between the sound passage and outlet 25 and between the valve passage and vent port 37.

It will be seen that there is provided a construction of an essentially practical nature in which the several objects of this invention are 15 attained.

As many possible embodiments may be made of the above invention without departing from the scope thereof, it is to be understood that all matter herein set forth or shown in the accompanying drawings is to be interpreted as illustrative and not in a limiting sense.

I claim:

1. In a sound modifier of the character described, in combination, a pair of relatively movable members provided with registrable passages, means for providing gradually decreasing communication between said passages as they are moved out of registry, means for simultaneously providing gradually decreasing communication 30 between one of said passages and the outside atmosphere, and means for relatively moving said members.

2. In a sound modifier of the character described, in combination, a valve housing, a tubular valve member rotatably mounted in said housing and having an end cut away to provide a gradually advancing wall surface, a vent port in said housing adapted to be gradually opened or closed to the interior of said valve member by 40 said wall surface upon rotation of said valve member, and means for rotating said valve member.

3. In a sound modifier of the character described, in combination, a valve housing, a tubular valve member rotatably mounted in said housing and having an end cut away to provide a helically advancing wall surface, a vent port in said housing adapted to be gradually opened or closed to the interior of said valve member by 50 said wall surface upon rotation of said valve member, and means for rotating said valve member.

4. In a sound modifier of the character described, in combination, a pair of inner and outer 55 members relatively rotatable about a common axis and provided with registrable sound passages, one of said members being formed with a helically advancing wall surface adapted to cooperate with a vent port in the other of said 60 members upon relative rotation being imparted to said members to gradually open or close said

passage to the outside atmosphere, and means for effecting relative rotation of said members.

5. In a sound modifier of the character described, in combination, a housing having formed therein a cylindrical valve chamber communicating with a coaxial inlet passage at an end of the housing and an outlet passage extending laterally through said housing, the relative positions of said passages being such that their axes intersect at an obtuse angle, a cylindrical valve 10 rotatably mounted in said valve chamber having formed therein connecting passages which in a certain position of said valve are respectively coaxial relatively to the said inlet and outlet passages and communicate therewith, and means 15 for maintaining restricted communication between said connecting passages and said outlet passage when said valve is turned away from said certain position.

6. A sound modifier comprising sound-transmitting means, sound-venting means having free access to the atmosphere, and an adjustable valve member for coordinately effecting a gradual closing of both the sound-transmitting and the sound-venting means at a single operation. 20 25

7. A sound modifier comprising sound-transmitting means, sound-venting means having free access to the atmosphere, and an adjustable valve member for coordinately effecting a gradual closing of both the sound-transmitting and the sound-venting means at a single operation or effecting a gradual opening of both said means 30 at a single operation.

8. In a sound modifier of the character described, in combination, a substantially unrestricted continuous sound passage, a housing member having an inlet port communicating directly with one end of said sound passage and an outlet port adapted during movement of said valve in one direction to communicate with the other end of said sound passage through an increasingly indirect path, a vent port in said housing adjacent said inlet port, and means on said valve member for gradually cutting off communication between said vent and inlet ports during 40 the said movement of said valve. 45

9. A sound modifier comprising a casing having a sound transmitting opening, a sound venting opening free to the atmosphere and means mounted in said casing for varying the extent 50 of said openings simultaneously in the same sense.

10. A sound modifier comprising a casing having a sound transmitting opening, a sound venting opening free to the atmosphere and a valve for coordinately effecting gradual variation of the extent of said sound transmitting and said sound venting openings in the same sense at a single operation. 55

LELAND D. NORTON. 60
